UNITED STATES PATENT OFFICE

172,839

COVERED POT

Ralph R. Olswang, Scarsdale, N. Y.

Application March 23, 1954, Serial No. 29,667

Term of patent 14 years

(Cl. D44—1)

To all whom it may concern:

Be it known that I, Ralph R. Olswang, a citizen of the United States, residing in Scarsdale, in the county of Westchester, State of New York, have invented a new, original, and ornamental Design for a Covered Pot, of which the following is a specification, reference being had to the accompanying drawing, forming a part hereof, in which:

Fig. 1 is an exploded view in perspective of a covered pot, showing my new design; and

Fig. 2 is a side elevational view thereof.

I claim:

The ornamental design for a covered pot, as shown.
